R. M. SEARLE

COPYHOLDER

Filed March 20, 1923

INVENTOR.
Robert M. Scarle.
BY David T. Simin
his ATTORNEYS.

Patented June 3, 1924.

UNITED STATES PATENT OFFICE.

ROBERT M. SEARLE, OF ROCHESTER, NEW YORK.

COPYHOLDER.

Application filed March 20, 1923. Serial No. 626,304.

To all whom it may concern:

Be it known that I, ROBERT M. SEARLE, a citizen of the United States, and resident of Rochester, in the county of Monroe and State of New York, have invented certain new and useful Improvements in Copyholders, of which the following is a specification.

The present invention relates to copy holders and more particularly to the type 10 in which a work supporting member and a line guide are relatively movable in order to obtain line spacing, and an object of this invention is to provide one or more adjustable light reflectors which will collect the 15 light and direct it upon that part of the work in immediate proximity to the line guide, so that artificial illumination in immediate proximity to the copy holder may be dispensed with.

To these and other ends, the invention 20 consists of certain parts, and combinations of parts, all of which will be hereinafter described: the novel features being pointed out in the appended claims.

25 In the drawings:

Fig. 1 is a side view of a copy holder constructed in accordance with this invention;

Fig. 2 is a face view of the copy holder;

Fig. 3 is a perspective view of a universal 30 joint by which one of the upright reflectors is supported; and

Fig. 4 is a sectional view through the reflector in immediate proximity to the line guide.

35 In the illustrated embodiment of the invention, a relative movement between a work holder and a line guide is effected, by providing a stationary frame 1 on which the work holder 2 is mounted to move preferably through a well known step by step mechanism, (not shown) controlled by a lever 3 pivoted at 4 to the frame. The work holder 2 has a work clamping means 5 arranged at its upper end to clamp the work

45 against the holder 2. The line guide comprises a plate 6 mounted to swing on the bar 7 which has arms 8 pivoted at 9 to the uprights 1 so that the line guide 6 may move toward and from the work support to accommodate work of different thicknesses 50 and may also be shifted vertically by shifting the arms 8 on the upright 1. This form of copy holder is old and well-known in the art and will not be described with further detail. The invention, of course, is not limited to copy holders of the type illustrated,

being designed for use with any copy holder where a line guide and a work support are relatively movable.

A copy holder is required to be used in a 60 large number of cases away from a source of illumination such as daylight or an artificial illumination. The provision of a lamp on the copy holder adds materially to the cost of the machine and many users of the copy 65 holders do not wish to be bothered with them, even though they have been provided. This invention obviates the use of a lamp attached to the machine and makes it possible to illuminate the field of work in proximity to 70 the line guide from a distant source of illumination either artificial or natural. A means for securing this result embodies a reflector 10 in the form of an elongated plate 75 pivotally mounted on the bar 7 which also forms a pivot for the line guide 6 herein-before described. This reflector may be arranged at any angle to the plane of movement of the work holder and extend horizontally thereover, thus permitting the collecting of light rays from an upward direction, as, for example, indicated by the dotted line in Fig. 1. At opposite sides of the work holder two upright reflectors 11 80 may be provided, these reflectors having a universal movement with reference to the work holder preferably through a universal joint supporting connection embodying a ball 12 secured by flanges 13 to the reflector and operating in a socket 14 which through 85 a strap 15 may be secured to a swinging arm. 90

8. It is apparent that the strap or sleeve 15 may be adjusted along the arm 8 with reference to the plane of movement of the line guide and through the ball and socket 95 joint may also be tilted in any direction, thus making it possible to gather the most desirable rays within a room and direct them upon a work support in a most advantageous position.

100 From the foregoing it will be seen that there has been provided a copy holder having means for gathering light rays from any suitable source and directing them upon the copy holder in the most desirable position. Reflectors for accomplishing different purposes may be so mounted with reference to the line guide that the relative movement between the line guide and the copy holder 105 does not affect the relative position of the light rays with reference to the line guide, thus enabling the user of the machine to 110

maintain a substantially constant illumination with reference to such line guide. This invention makes it possible for the user of a machine to obtain daylight illumination of the work, notwithstanding the position of such user with reference to the direction with which such daylight illumination is received into the room. It is also possible for the user of the machine to obtain illumination from a distant artificial source of illumination in a room.

What I claim as my invention and desire to secure by Letters Patent is:

1. In a copy holder, the combination with a line guide and a work support, one of which is movable relatively to the other for producing line spacing, of reflecting means mounted on the copy holder for maintaining illumination of the work fixed with relation to the line guide, said reflecting means being adjustable with reference to the line guide so that the fixed position of the illumination with relation to the line guide may be changed.
2. In a copy holder, the combination with a line guide and a work support relatively adjustable for producing line spacing, of a reflector, and means for supporting said reflector in fixed relation to the line guide during the relative movement between the line guide and the work holder, said reflector being adjustable relatively to the line guide.
3. In a copy holder, the combination with a line guide and a work support adjustable relatively for producing line spacing, of a reflector, and means for supporting the reflector in a fixed relation to the line guide at one side of the work support and in a fixed relation to the line guide during the relative movement between the work support of the line guide, said reflector having a universal adjustment relatively to the line guide.
4. In a copy holder, the combination with a line guide and a work support adjustable relatively for producing line spacing, of two reflectors, and means for supporting said reflectors on opposite sides of the work support and in fixed relation to the line guide, when a relative movement between
- the line guide and the copy holder takes place.
5. In a copy holder, the combination with a line guide and a work support adjustable relatively for producing line spacing, of two reflectors, and means for supporting said reflectors on opposite sides of the work support and in fixed relation to the line guide when a relative movement between the line guide and the copy holder takes place, said supporting means having provision for permitting the adjustment of the reflectors relatively to the line guide.
6. In a copy holder, the combination with a line guide and a work support adjustable relatively for producing line spacing, of two reflectors, means for supporting said reflectors on opposite sides of the work support and in fixed relation to the line guide when a relative movement between the line guide and the copy holder takes place, said supporting means having provision for permitting the adjustment of the reflectors relatively to the line guide, and another reflector, and supporting means for the same permitting the reflector to swing about an axis extending longitudinally of the line guide.
7. In a copy holder, the combination with a stationary support, and a work supporting member movable on said support, of a line guide, a bar on which said line guide is mounted to turn having arms at opposite ends pivotally supported on the stationary support, a reflector and a support connecting said reflector with one of the arms of the bar on which the line guide turns, said supporting means having provision permitting universal movement of the reflector with reference to the line guide.
8. In a copy holder, the combination with a stationary support, and a work supporting member movable on said support, of a line guide, a bar on which said line guide is mounted to turn having arms at opposite ends pivotally supported on the stationary support, and a reflector mounted to turn on said bar about an axis parallel with the longitudinal axis of the line guide.

ROBERT M. SEARLE.
